POURING SPOUT

Stevens A. Bennett, Chicago, Ill., assignor to
 Wilson & Bennett Manufacturing Company,
 Chicago, Ill., a corporation of Illinois

Application March 16, 1935, Serial No. 11,391

1 Claim. (Cl. 221—11)

This invention relates to cans or pails provided with pouring spouts which may be either fixed or rotatable, but preferably rotatable, and is particularly directed to novel means for covering such pouring spout.

The objects of the invention are to provide a can or container having a pouring spout with a novel cap or cover; to provide a rotatable pouring spout with a cap or cover which is hinged at one side and is adapted to be swung laterally with respect to the spout so that the pourer or user of the can may not only conveniently operate the same but will have full visibility of the pouring operation. Furthermore by hinging the cover to the side of the spout it will tend to remain in open position while the pouring is going on and is not apt to swing down to interfere with the contents passing out of the spout.

Other objects and advantages will appear from the following description and the accompanying drawing, in which,

Figure 1 is a plan view of a pail or can showing my improved spout and cover;

Figure 2 is a sectional view taken on the line 2—2 of Figure 1; and

Figure 3 is a sectional view taken on the line 3—3 of Figure 1.

As shown in this drawing, 4 represents a pail or can having a top or head 5 with a nozzle 6 which may be formed integrally therewith or attached thereto. The pouring spout 7 has an annular portion 8 which is engaged by or coacts with the nozzle in any suitable or well known manner to hold the spout securely thereon. Such attachment may be such that the spout is held in fixed position with its nose or discharge end 9 projecting outwardly over the rim of the cover, or it may be rotatably mounted so that it can be swung back out of the way as shown in Figure 1. The nozzle may be provided with any suitable plug or sealing means, not shown, for sealing the receptacle either initially or from time to time as the contents are poured out.

The spout 7 has a bottom or pouring lip 10 and an upwardly projecting flange forming side walls 11. The flange is substantially semi-circular in the rear portion thereof and the sides converge toward the outer end as shown in Figure 1.

The spout cap or cover 12 is shaped to con-

form to the shape of the spout and comprises a top plate or portion 13 with a downwardly depending annular flange or sides 14 which fit closely over the bead or rim 15 around the top of the spout. A portion of the flange or side wall 14 is split or cut to form a tongue 16 which engages with a slot 17 in the side of the spout, thereby forming a substantial hinge for the cover. The parts forming the hinge may be pressed together in order to provide sufficient friction to hold the cover in any adjusted position.

Another portion of the flange or rim 14 is cut or split on the side approximately opposite from the hinge to provide a fastening tongue or clip 18 as best shown in Figure 3. This clip springs 15 over the adjacent portion of the bead 15 and serves to hold the cover in tightly closed position.

This improved cover may be quickly operated and serves to prevent dirt or dust, flies or insects, from entering the container or collecting on the spout. This is a particularly desirable feature when the containers are used for oil or other similar liquids.

When the contents of the pail are to be discharged the operator swings up the cover 14, 25 which is preferably hinged on the left-hand side of the spout as the container is ordinarily held for pouring, and then removes the plug or closure and proceeds with the pouring. It will be noted that the position of the cover when swung up 30 or over to open position is such that it will not tend to flop or swing back over the spout and will not interfere with the vision of the operator.

Having thus described my invention, what I claim and desire to secure by Letters Patent is:

The combination with a container having a head, of a pouring spout attached thereto and having an annular portion with a lip extending over the rim of the container and having upwardly projecting sides, and a cover having an annular flange adapted to fit over the spout, a portion of said flange being cut to form a hinge member which engages with a slot in the side of the spout and another portion of the flange being cut to form a clip for engagement with the side of the spout to hold the cover in closed position.

STEVENS A. BENNETT.
